US00D613003S

(12) United States Design Patent
Miller et al.

(10) Patent No.: US D613,003 S
(45) Date of Patent:  Mar. 30, 2010

(54) PET GROOMING TOOL

- (75) Inventors: Channing Miller, Fort Lauderdale, FL (US); Gary Rapps, Sunrise, FL (US); Raul Chinda, Fort Lauderdale, FL (US)
- (73) Assignee: Sunbeam Products, Inc., Boca Raton, FL (US)

() Term: 14 Years

(21) Appl. No.: 29/328,256

(22) Filed: Nov. 21, 2008

(51) LOC (9) Cl. 30-99

(52) U.S. Cl. D30/158

(58) Field of Classification Search ..... D30/158-159, D30/199; 119/600, 601, 604-606, 611-619, 119/625, 628-633, 624; D4/132-138, 100-102, D4/122, 127, 119, 114, 199, 118, 121, 159, D4/129, 130, 116, 18, 117, 120; D8/106, D8/107, 13, 45, 80; 401/28, 201, 6, 284, 401/279, 288, 22, 140, 207, 149, 281, 136, 401/137, 188 R, 189, 190, 268, 270, 278; 132/119-121, 152, 154, 147-150, 108-110, 132/112-115, 160; D28/31, 63, 30, 25, 21, D28/7, 34; 15/50.1-50.3, 55, 57, 71, 77, 15/79.1, 104.002, 105-106, 143.1, 159.1, 15/160, 186-188, 169, 145, 114, 231, 172, 15/1.52, 207.2, 29, 229.13, 111, 118, 109.94, 15/164, 209.1, 211, 236.06, 236.01, 236.05, 15/210.1, 229.11, 244.3, 191.1; 56/400.01, 56/400.17, 400.21; 81/177.7, 489, 177.1, 81/436-440, 849; 16/426, 421, 422, 438, 16/110.1, 430, DIG. 12, DIG. 19; 30/353; 19/98; 294/104, 19.1, 3; 601/138, 114, 17, 601/160, 112, 154, 137; 604/289; D24/215, D24/214, 206; D32/40, 42, 45, 35, 41; D7/393, D7/395, 401.2

(57) CLAIM

The ornamental design for a pet grooming tool, as shown and described.

DESCRIPTION

FIG. 1 is a front right perspective view of the pet grooming tool showing the new design;

FIG. 2 is a front elevation view thereof;

FIG. 3 is a back elevation view thereof;

FIG. 4 is a right side elevation view thereof;

FIG. 5 is a left elevation view thereof;

FIG. 6 is a top plan view thereof; and,

FIG. 7 is a bottom plan view thereof.

The broken lines in the drawings are for illustrative purposes only and form no part of the claimed design.
